UNITED STATES PATENT OFFICE.

JOSEPH BAKER INGALLS, OF CHICAGO, ILLINOIS.

CASING FOR COIN BANKS.

Original application filed February 23, 1923, Serial No. 620,819. Divided and this application filed May 19, 1925. Serial No. 31,437.

This invention is a casing for coin banks, the present application being a division of an application filed by me February 23, 1923, Serial No. 620,819.

5 The object of the present invention is to provide a simple and inexpensive casing for the operating mechanism which will effectually enclose the mechanism and will be free of visible securing devices but may be readily released to permit withdrawal of the coins after the predetermined number has been deposited.

In the drawings:

15 Figure 1 is a perspective view of the closed bank,

Figs. 2, 3 and 4 are perspective views of different members of the casing, and

Fig. 5 is a detail section on the line 5—5 of Fig. 1.

20 In carrying out my invention, I employ an outer or back casing member consisting of a plate 1 having a flange or rim 2 across one end and side rims 3 along its sides extending from the rim 2, the end of the plate 25 opposite the end having the rim 2 being free of all rims or projections and all the rims being constructed with overhanging inwardly projecting flanges 4. This member of the casing may be stamped from sheet 30 metal of proper gage and will obviously be capable of very economical and rapid production. In the rim 2 are formed slots 5 and 6 for a purpose which will presently appear and at any convenient point in the 35 back plate 1 is a threaded opening 7. The casing also includes an intermediate member shown in Fig. 3 and comprising a back plate 8 having an opening 9 therethrough adapted to register with the opening 7 in 40 the plate 1. Rims or walls 9 rise from the side edges of this plate but terminate short of the lower end thereof, the said walls or rims 9 being connected by a transverse rim or wall 10 at one end of the plate, which 45 rim or wall 10 is constructed with slots 11 and 12 adapted to register with the slots 5 and 6, as will presently appear. A front plate 13 is secured upon the edges of the rims or walls 9 and 10 by suitable screws, 50 indicated at 14, inserted through the said front plate and engaging bosses on the plate 8 in a well-known manner. The front plate 13 is provided with openings 15 to receive the ends of the hubs or shafts of counting 55 wheels, and sight openings 16 are also

formed in the said front plate to permit reading of the indicators upon the counting wheels. The front plate is given an irregular outline which will correspond to the form of a partition 17 so that below the said partition a chamber for the reception of the deposited coins will be provided and above the said partition a closed chamber will be provided in which the operating mechanism will be housed. The cover or face plate 18 60 is a flat plate of rectangular outline and of the same area as the intermediate member of the casing and said plate 18 is adapted to extend over the said intermediate member so as to cover the entire front of the same. The 65 said face plate 18 is provided at its lower end with a rim 19 upon which is an external knob or projection 20 to facilitate the removal of the cover when the bank has been filled, and at the sides of the said face plate 70 are flanges or rim members 21 which are adapted to abut the lower ends of the rims 9 of the intermediate member of the casing so as to lie flush therewith and, in effect, form continuations of the same. The rim or 75 flange member 21 which lies against the extended portion 22 of the face plate 13 is provided with an opening 23 therein which is adapted to be engaged by the lower end of a latch or locking lever 25 housed within 80 the intermediate member of the casing and adapted to be actuated by the counting devices. In actual practice, the counting wheels are provided with elements adapted to act upon the latch whereby, when the first 85 coin is inserted, the latch will be moved into locking position and when the last coin of the predetermined number is inserted the latch will be actuated to be withdrawn from the locking position and the cover member 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

keyholes 27 will be provided in the back plate and the intermediate member of the casing, as indicated, and the key, indicated at 29, will, of course, be kept by the custodian.

When the latch has been released, the coins are removed by merely pulling the outer or front member of the casing from its position over the intermediate member of the casing, whereupon the open end of the casing will be exposed and the coins may drop out. The rim members 2 and 3 of the back member or outer member of the casing are of such height that the intermediate and front members of the casing will be snugly received therein and will be held frictionally thereby, the fit being such that, while the intermediate and front members of the casing may be easily inserted without binding, the engagement will be sufficiently tight to prevent accidental withdrawal unless the latch be released, and a single screw inserted through the opening 9' of the back plate of the intermediate member of the casing into

the opening 7 in the back plate 1 will securely hold the parts together.

Having thus described the invention, I claim:

A coin bank including a casing consisting of a back member having one open end and provided with upstanding rim sections having overhanging flanges, an intermediate member having rim elements around part of its edge portion, said intermediate member being secured within the back member and housing the operating mechanism, and a front member covering the intermediate member and fitting under the overhanging flanges of the back member and slideable therefrom, said front members having rim portions at one end abutting and lying flush with the rim portions of the intermediate member, and means housed within the intermediate member for locking the front member in place.

In testimony whereof I affix my signature.
JOSEPH BAKER INGALLS. [L. s.]
